MULTIPLE LANE MAGNETIC SOUND RECORDING SYSTEM

Herman S. Heller, West Los Angeles, Calif.

Application January 22, 1938, Serial No. 186,351

5 Claims. (Cl. 179—100.2)

This invention relates generally to methods of and apparatus for magnetically recording sound.

A shortcoming of magnetic sound recording methods and apparatus as known heretofore has been that, in order to secure recordation of all of the desired frequencies, the magnetic recording wire or tape has to be driven at such a high speed that it was not possible to make a continuous recording of a desirable duration on a convenient length of the recording wire or tape.

It is accordingly a primary general object of the present invention to provide a magnetic recording machine and method in accordance with which a recording of comparatively long duration may be made on a recording element of a normal or convenient length.

Reference is here directed to a copending application filed by Herman S. Heller and Leo G. Butler, entitled "Method of and apparatus for magnetically recording sound," filed October 25, 1937, Ser. No. 170,988, in which is disclosed one means and method for securing a long duration recording on a recording element of comparatively short or normal length. In accordance with the invention disclosed in said copending application, the magnetic element, preferably in the form of a tape, is driven through the machine first in one direction and then in the other, a recording being made on the tape during each such trip, and successive recordings being spaced laterally of one another on the width of the tape, a multiplicity of sets of recording coils and pole pieces being provided, one allotted to and positioned opposite each recording lane. These sets of recording coils are used successively as the tape is driven first in one direction and then in the other, so that successive recordings are made on the single tape, one next to the other across the width of the tape. In accordance with the present invention, a multiplicity of recordings is made on adjacent longitudinally extending lanes of the tape, but this is accomplished by shifting the relative position between the tape and the recording coils and pole pieces each time the tape reverses direction, the tips of the pole pieces being only sufficiently wide to affect a limited width of the tape on each trip of the tape through the machine, so that there is again provided a multiplicity of successively made recordings extending longitudinally of the tape. It will of course be evident that the recording coils may be stationarily mounted and the tape shifted transversely at the end of each trip past the coils, or the tape may be arranged for travel along a

fixed line of travel, and the recording coils shifted transversely of the tape a proper distance each time the tape reverses direction. The generic claims broadly covering multiple lane recording are made in the aforementioned copending application, claims in the present application being drawn to a system in which there is relative transverse shifting between the recording coils and tape.

10 With this preliminary discussion in mind, the invention itself will be most readily understood from the following detailed description of present preferred embodiments thereof, reference for this purpose being had to the accompanying drawings, in which:

Fig. 1 is a front elevation of a recording machine in accordance with the present invention;

Fig. 2 is a section taken on line 2—2 of Fig. 1; 20 Fig. 2a is a detail showing an anchoring means on the end of the recording tape;

Fig. 3 is a section on line 3—3 of Fig. 1;

Fig. 4 is a section on line 4—4 of Fig. 3;

Fig. 5 is a fragmentary view looking toward 25 the machine as though viewed from the right in Fig. 3;

Fig. 6 is a detail section on line 6—6 of Fig. 3;

Fig. 7 is a simple, typical wiring circuit for the system;

30 Fig. 8 is a view similar to Fig. 3 but showing a modification;

Fig. 9 is a view taken as indicated by line 9—9 of Fig. 8, certain parts being broken away;

Fig. 10 is a perspective view of a typical pole 35 piece;

Fig. 11 is a section on line 11—11 of Fig. 2; and

Fig. 12 is a section on line 12—12 of Fig. 2.

The exemplification of the invention illustrated in the drawings has a supporting panel 15, preferably, though not necessarily, vertically disposed, and spaced forwardly of supporting panel 15, a vertical panel 16 adapted to carry certain members and serving to enclose portions 40 of the driving gear located forwardly of supporting panel 15. As here shown, panel 16 is supported from panel 15 by means of supporting brackets or wall members 17 (see Fig. 2).

Mounted on and extending through panel 15 50 as a tubular bearing member 18 having bushings 19 and 20 within which is journaled spindle 21, the latter being provided with a reduced portion 22 extending forwardly through an opening 23 in front panel 16.

Tightly mounted on spindle portion 22, imme-

diately forwardly of bushing 19, is a belt pulley 25, and just forwardly of pulley 25 is an equal diameter pulley 26 which is tightly mounted on the inner end of a sleeve 27 which is mounted on a bearing bushing 28 rotatable on spindle portion 22. The outer end of sleeve 27 is supported by a bearing bushing 30 which is rotatable on a portion 31 of spindle 21 reduced to a diameter smaller than that of portion 22. The extremity 32 of spindle 21 is reduced still further, and has tightly mounted thereon an annular member 33 of the same outside diameter as the reduced outer end 34 of sleeve 27. A pair of reels 35 and 36 for the magnetic tape are mounted in concentric, closely spaced relation on member 33 and sleeve portion 34, respectively. The reels are keyed on said members, as indicated at 37, and are preferably arranged for ready demountability. For example, the hub portion 40 of the reels may be arranged for sliding engagement with members 33 and 34, and may be releasably retained thereon by any suitable spring clamp devices as indicated at 39. A preferred type of reel and mounting, partially indicated in the drawings, is more fully disclosed and claimed in my copending application, entitled "Reel for magnetic recording tape," Ser. No. 170,987, filed October 25, 1937.

Each of reels 35 and 36 has a central hub portion 40 to which the magnetic tape M may be anchored, in any suitable manner, and on which said tape is reeled. For example, as indicated in Fig. 2a, the end of the tape may be provided with an anchor piece 41 adapted to be engaged in a key-hole slot 42 formed in hub member 40. The tape is wound on the hub of reel 35 in such direction that it may extend toward the right, in the aspect of Fig. 1, from the bottom of the roll, as clearly indicated in Fig. 1, the reel thus turning in a counter-clockwise direction, as viewed in Fig. 1, as tape M is fed therefrom, or in a clockwise direction as the tape goes onto said reel. Assuming the tape to be fed from reel 35, it is taken toward the right, as viewed in Fig. 1, to pass under and then upwardly from a drive pulley 46. This pulley 46, which is preferably alined with reel 35 (see Fig. 2) is tightly mounted on the reduced extremity of a drive shaft 47 journaled for rotation in bushings 48 and 49 supported by a tubular bearing member 50 mounted on and extending through supporting panel 15, said shaft passing through an opening 51 in front panel member 16. Means for driving shaft 47 will be explained later. Tape M is pressed into driving engagement with pulley 46 by a spring-pressed idler roller 52. This idler roller 52, which engages the tape and presses it against the tread 46a of pulley 46 between pulley flanges 46b, is carried by a yoke 54 furnished with a guide stem 55 which non-rotatably but slidably engages a bracket or support 56 mounted on panel 16.

From drive pulley 46, tape M passes upwardly through a polarizing and translating magnet unit or tone head 60 to an idler pulley 61, and after passing over pulley 61, the tape is taken to inner reel 36. The tape goes on to the upper side of the roll reeled on reel 36, being wound thereon by counter-clockwise rotation of reel 36 during drive of the tape from reel 35 to reel 36. Of course, when drive pulley 46 turns right handedly, the tape is driven from inner reel 36 over idler pulley 61 and drive pulley 46 is outside reel 35, reels 35 and 36 rotating in a clockwise direction.

The tape may, if desired, be given a twist between pulley 61 and reel 36, in order to enable it to go onto reel 36 more readily, though this is not necessary and the tape is not so illustrated in the drawings.

Mounted on the rearward end of shaft 47 is a belt pulley 68, driven through belt 67 from pulley 68 pinned on a shaft 69 driven through reduction gear set 70 from electric drive motor 71.

- 10 Means are provided for driving inside reel 36 and allowing outside reel 35 to idle when drive pulley 46 is being driven in such direction as to drive tape M from reel 35 to reel 36, and to drive outside reel 35 and allow inside reel 36 to idle 15 when drive pulley 46 is driving the tape in the reverse direction. For this purpose, the aforementioned pulleys 25 and 26 are connected by belts 95 and 96 with pulleys 97 and 98, respectively, arranged for alternate drive from shaft 20 47 as said shaft is rotated in one direction or the other. As a simple and preferred means to this end, pulleys 97 and 98 are driven through one-way drive clutches, here shown as roller-ratchet clutches 100 and 101, respectively, from 25 drive shaft 47, said clutches being arranged to drive alternately as shaft 47 is rotated in one direction or the other. Pulleys 97 and 98 are mounted on the outer ring portions 103 of the roller ratchet clutches, the inner members 104 30 of the clutches, which are provided with the usual notches 105 and rollers 106, being keyed on shaft 47. As will be evident from Figs. 11 and 12, pulley 98 is driven through roller ratchet clutch 101 when shaft 47 is rotated in a counter-clockwise direction, as viewed from the front of the machine, while pulley 97 is driven through roller ratchet clutch 100 when shaft 47 is rotated in a clockwise direction. Accordingly, when shaft 47 is driven from motor 71 in a counter-clockwise direction, pulley 46 on the end of said shaft drives tape M from outside reel 35 toward inside reel 36, and pulley 98 is driven through roller ratchet clutch 101 to drive reel 36 to take the tape up properly. At the same time, pulley 45 97 idles on shaft 47, reel 35 being rotated simply by the tape which is being fed from it. And when pulley 46 is being rotated by shaft 47 and electric motor 71 in a clockwise direction, so as to drive tape M from inside reel 36 toward outside reel 35, outside reel 35 is driven through roller ratchet clutch 100, belt 95 and pulley 25 50 to take up the tape properly, inside reel 36 at this time rotating freely as the tape is drawn therefrom.
- 55 The relations of the driving gear should be such that the reel which is acting as the supply reel will not be rotated by the tape at such a speed, as the roll of tape on the reel approaches its minimum diameter, as to drive rearwardly through pulley 25 or 26, as the case may be, at a sufficiently high speed to cause the corresponding pulley 97 or 98 to overtake the inner driven member of its roller ratchet clutch and thus tend to drive said inner member faster than it is being rotated by shaft 47. Any such tendency would of course be relieved by slippage of belts 95 or 96, as the case might be. However, this condition is avoided by properly relating the diameters of pulleys 97 and 98 to pulleys 25 and 26 as well as the diameter of pulley 46 to the diameter of the hubs of the two reels. Preferably, in order to safeguard against this condition, pulleys 25 and 26 are made of slightly smaller diameter than pulleys 97 and 98, and the effective diameter of pulley 46 is no greater

than the diameter of the hub portion 40 of the reels. With this arrangement, there is positive assurance that the supply reel cannot drive rearwardly in the manner described. This arrangement also provides a desirable overdrive on the reel which is acting as the take-up reel.

Preferably, pulleys 25 and 26 are provided with spring pressed friction shoes 25a-26a, respectively, which serve to prevent overrunning of the reels.

Tone head 60, best shown in Figs. 3 and 4, embodies two rectangular insulation blocks 110 and 111. A pair of headed pins 112 pass with sliding fit through block 111 and tightly engage block 110. Block 111 is thus movable toward and from block 110 on pins 112, the opposing faces of the two blocks being in engagement with one another when the device is in operating position. Preferably, pins 112 have hinge joints 113 permitting block 111 to be swung open from block 110 after being pulled outwardly on pins 112. This opening arrangement, which is of great convenience in threading the recording tape between the two blocks and in inserting or removing the pole pieces in the device, is disclosed and claimed in my copending application entitled "Sound head for magnetic recording machine," Serial No. 170,985, filed Oct. 25, 1937, now Patent No. 2,229,326 of Jan. 21, 1941.

As here shown, block 110 is mounted on the outer end of a plug member 116, which is adapted to be removably inserted in a socket member 117 mounted on the outer end of a hollow shaft member 119 having a longitudinally sliding fit within a bore 120 formed in a mounting member 121 secured to panel 15. Shaft 119 is held against rotation by a key 122 and a keyway 123, all as clearly shown in Fig. 3. Shaft 119 is hollow, as illustrated in Fig. 3 and serves as a conduit for a cable 119a connected to the tone head.

Mounting member 121 is formed with a pair of oppositely extending arms 125 and 126 which curve around opposite ends of the tone head. The ends of these arms are provided with portions 127 having flat faces 128 coplanar with the meeting faces of sound head blocks 110 and 111. Hinged on each of arm portions 127 is a cover plate 130 having a plane surface 131 adapted to meet surface 128. The hinged portion 132 of cover plate 130 is engaged by a flat spring member 133 which yieldingly holds member 130 in face to face engagement with arm portion 127.

The described opposed faces 128 and 131 are formed in each instance with a longitudinally extending groove or way 134a adapted to receive and pass the recording tape. For example, assuming use of a tape of .002" in thickness and .125" in width, this way may be .003" in depth and .126" in width. The way should be only sufficiently larger than the cross-sectional size of the tape to permit the tape to be drawn freely therethrough. Arm portion 127 and cover plate 130 may be grooved in such a manner that the depth of this way 134a lies half within each of said members when the members are in face to face engagement, as in Fig. 4 and Fig. 6. The two ways thus provided at the ends of oppositely extending arms 125 and 126 are in alignment with one another, and are located opposite the ends of tone head blocks 110 and 111, as illustrated.

The opposed faces 110a and 111a of blocks 110 and 111 are formed with a longitudinally extending groove or way 134 adapted to receive and pass the recording tape. This way, which

is aligned with the aforementioned ways 134a is of the same depth as ways 134a, but of greater width. Way 134 may, for example, be approximately 50% greater in width than ways 134a. 5 Blocks 110 and 111 may be grooved in such a manner that the depth of way 134 lies half within each block when the two blocks are in face to face engagement.

Three pairs of electromagnets are mounted in 10 blocks 110 and 111. Thus, a pair of recording or translating electromagnets R are mounted in blocks 110 and 111, with their axes intersecting the center line of way 134. A pair of erasing or polarizing coils E₁ and a second pair of erasing or polarizing coils E₂ are mounted in blocks 110 and 111 above and below recording coils R, respectively, with their central axes also intersecting the center line of way 134.

Each of the recording and erasing magnets 20 comprises a wound magnetic bobbin 140 provided with a central aperture 141 of rectangular cross section for the magnetic pole piece 142. Bobbins 140 are received within cylindrical magnetic sheath 140a tightly mounted within insulation block 110 or 111, as the case may be.

Pole pieces 142 (see Fig. 10), of rectangular cross-section, are slidably mounted in apertures 141, and their inner ends are beveled and tapered to an edge preferably not over approximately .003" in thickness and of a dimension at right angles to the tape approximately, or slightly less than, one-half of the width of the tape (assuming two-lane recording). The pole pieces may be formed initially with a comparatively sharp, chisel-like edge 142a, but by reason of wear on the tape are soon blunted somewhat and operate satisfactorily, with comparatively slow speed of tape, at a thickness dimension of approximately .003" as stated above.

40 The outer ends of pole pieces 142 are engaged by plunger members 150 pressed lightly against the pole pieces by means of compression springs 151 mounted in housings 152 carried by plates 153 which are mounted on the insulation blocks, as in the manner clearly illustrated in Fig. 4.

In the embodiment of the invention here shown, the pole pieces of each pair of erasing magnets are somewhat offset from one another in a direction longitudinally of way 134, while the recording magnet pole pieces are directly opposite one another, as clearly indicated in Fig. 4.

The tape moving between pulleys 46 and 61 (see Fig. 1) is received within and guided by ways 132 formed in the ends of arms 125 and 126, 55 and between ways 134a, passes through way 134 formed between recording head blocks 110 and 111. Way 134 within the recording head has been described as of a width greater than that of the tape, and the recording head is accordingly capable of transverse movement relative to the tape. Thus, a recording having been made along one edge of the tape with the recording head positioned, for example, as seen in Fig. 3, then the recording head may be moved toward the right, as seen in Fig. 3, thereby shifting the position of the recording head pole pieces laterally with relation to the tape, after which a second recording may be made on the tape parallel to and adjacent the first.

60 Means for so shifting the recording head will now be described. Shaft 119 which supports the recording head extends through an opening 160 in panel 15, its rearward end being supported by a tubular boss 161 extending within opening 160, said boss 161 being formed on a mounting mem-

ber 162 secured to the rearward side of panel 15 as by means of screw 163. Secured against member 162 by said screw 163 is a plate 164, the inner surface 165 of which overlies the rearward end of shaft 119. The rearward end portion of shaft portion 119 is formed with screw threads 166 of relatively coarse pitch, and mounted on the screwthreaded portion of shaft 119, between surface 165 of plate 164 and the opposed surface 162a of mounting member 162 is a nut member 167, provided with an extending arm 168 (see Fig. 5). Nut member 167 is confined against axial movement between surfaces 165 and 162a, but is freely rotatable therebetween. It will be evident that rotation of nut member 167 will effect longitudinal travel of shaft 119 and sound head 60 carried thereby. Threads 166 are of such pitch that operation of shaft 168 through the angular travel indicated in Fig. 5 will move shaft 119 through a distance just sufficient to move the sound head from a position in which magnetic tape T (indicated in Fig. 3 in dotted lines) is adjacent one edge of way 134 to a position in which said tape is adjacent the other edge of said way. Accordingly, when operating arm 168 is in one position, the pole pieces of the magnets will be opposite and operate on one half of the tape, and when arm 168 is shifted to its other position, said pole pieces will lie opposite and operate on the other half of the tape. The two operating positions of the sound head are established by stop pins 170 and 171 which are engaged by arm 168 when one side or the other of way 134 is adjacent the edge of the tape guided by fixed ways 134a of arms 125 and 126.

Connected to the swinging end of arm 168 is a link 175, the other end of which is connected to the movable plunger 176 of a solenoid 177. Energization of solenoid 177 moves arm 168 from the full line position of Fig. 5 to the dotted line position of said figure, while a compression spring 178 acting between the ends of solenoid 177 and a flange 179 on link 175 returns arm 168 to the full position of Fig. 5 when solenoid 177 is deenergized. Thus, when solenoid 177 is deenergized, a recording is made on one half of tape T, while energization of solenoid 177 causes movement of arm 168 from the full to the dotted line positions of Fig. 5, thereby shifting shaft 119 and sound head 60 sufficiently to move the recording pole pieces over to the other half of tape T so as to effect a recording on said other half of the tape.

A typical electrical circuit for the system is shown in Fig. 7. The aforementioned drive motor 71 for the mechanism is designated by the same numeral in Fig. 7, its armature being indicated as connected by leads 200 and 201 across the power supply line, and its field winding 202 being indicated as connected through a polarity reversing switch S across said leads 200 and 201. Polarity reversing switch S is here indicated as comprising an insulation member 204 carrying a pair of conductor members 205 and 206. When member 204 is moved in one direction, conductor members 205 and 206 make with pairs of contacts 207, 208 and 209, 210, respectively, and when insulation member 204 is moved in the opposite direction, conductor members 205 and 206 make with contacts 211, 212 and 213, 214, respectively. Contacts 207 and 213 are connected to one field winding lead 215, while contacts 211 and 209 are connected to the opposite field winding lead 216. Contacts 208 and 212 are connected to a lead 217 connected to power supply lead 201,

while contacts 210 and 214 are connected by lead 218 to power supply 200. It will be evident that when switch S is in the position illustrated in Fig. 7, the field winding 202 of motor 71 is energized with one polarity with reference to the armature of the motor, and that when member 204 of switch S is moved so as to bring conductor member 205 against contacts 211 and 212 and conductor member 206 against contacts 213 and 214, the polarity of the field with reference to the armature will be reversed, and the motor will therefore run in the reverse direction. The tape is therefore driven through the machine in one direction or the other, depending upon the position of switch S. It may here be noted that while switch S may here be considered simply as a manually operated switch, it may of course be operated automatically as the tape reaches the end of its travel in each direction.

The previously described recording magnets R and erasing magnets E₁ and E₂ appear in Fig. 7, the windings of each pair of magnets being connected in series, as indicated. As here typically shown, the erasing magnets are energized by direct current, though of course any other suitable type of erasing magnet current may be employed if desired. Thus, series connected pairs of magnets E₁ and E₂ are here shown as connected at one side by leads 220 and 221, respectively, to one side of a battery 222, the other side of said battery being connected by conductor 223 to the movable arm 224 of a control switch 225. Switch arm 224 is movable between two contacts 226 and 227, contact 226 being connected by wire 228 to recording magnets E₁, and contact 227 being connected by wire 229 to recording magnets E₂. Thus, when switch arm 224 is moved in one direction, so as to make with contact 226, magnets E₁ are connected in circuit with battery 222, and when switch arm 224 is moved in the opposite direction, so as to make with contact 227, magnets E₂ are connected in circuit with battery 222.

Switch arm 224 is moved between contacts 226 and 227 by a projection 230 on operating arm 168 (see Fig. 5). When solenoid 177, diagrammatically shown in Fig. 7, is energized, its movable core, which is operatively interconnected with switch arm 224, moves in such manner as to allow said arm 224 to make with contact 226, thus connecting erasing magnets E₁ in circuit and moving the sound head to record on one half of the tape; and when solenoid 177 is deenergized, its core 176 moves under the influence of spring 178 to swing arm 168 in an upward direction, thereby moving switch arm 224 into contact with contact 227, at which time erasing magnets E₂ are energized and the sound head is positioned to record on the other half of the tape.

In the simple form of the invention here shown, energization of solenoid 177 is controlled by a circuit 235 including a battery 236 and a switch 237.

It is to be understood that when a recording is to be made on either lane of the tape, erasing magnets E₁ or E₂ are connected in circuit, depending upon the direction in which the tape is to run, the erasing magnets which are ahead of the recording magnets for a given direction of the tape being used. These erasing magnets, supplied with direct current from battery 222, produce a magnetic flux through the tape between the erasing magnet pole pieces, and cause the tape to be magnetized to saturation, thereby obliterating any prior recording on the lane of

the tape covered at that time by the erasing pole pieces. The recording coils are at the same time energized by a voice or sound current, producing a varying flux through the tape between the tips of the recording coil pole pieces, and thereby effecting a magnetization of the lane of the tape covered by said pole pieces, corresponding to the fluctuations of the voice or sound current. The resulting magnetized sound record on the tape is subsequently reproduced by running the tape between a pair of reproducing magnets which may either be the same magnets used for recording, or may be similar magnets on a reproducing machine. In order to avoid erasing of the record during reproduction, a switch 234 is provided in circuit 223, which is opened during reproduction of the record.

One side of recording magnet R is connected by a conductor 250 to contacts 251 and 252 of a record-reproduce switch 254. A microphone M is connected via leads 255 and 256 across contacts 257 and 258, respectively, of switch 254. When switch 254 is thrown to "record" position, a switch arm 259 makes with contact 258, a switch arm 260 makes with contact 257, and a switch arm 261 makes with contact 251. Switch arm 259, thus connected to microphone lead 256, is connected by lead 262 to one end of the primary winding 263 of an amplifier input transformer 264, while switch arm 260, connected to the other microphone lead, is connected by lead 265 to an intermediate tap of the primary of input transformer winding 263. The secondary winding of transformer 264 is connected to the input end of an amplifier 268, typically of the vacuum tube type. Output leads 269 and 270 of amplifier 268 are connected to switch arms 261a and 261, respectively, then making with contacts 251 and 251a, and are therefore connected across recording magnet leads 250 and 250a. Microphone M is thus connected through switch 254 and amplifier 268 to recording magnets R, so that a speech or music input to the microphone produces a corresponding sound current which, after amplification, flows in said recording or translating magnets R.

When switch 254 is moved in the opposite direction, to "reproduce," switch arms 259 and 274 make with contacts 275 and 252, respectively, contact 275 being connected by wire 277 to recording coil lead 250a, and contact 252 being connected by wire 278 to recording coil lead 250. At the same time, switch arms 261a and 261 make with contacts 280 and 281, respectively, which are connected by leads 282 and 283 to a speaker 284. Switch arm 274 is connected by lead 285 to the end of primary transformer winding 263 opposite the end to which lead 262 is connected. Translating coils R are then connected through switch 254 and amplifier 268 to speaker 284, so that if a tape T having a previous recording thereon is run in proper direction through the machine, with erasing circuit switch 234 open, the recording on whichever lane of the tape is positioned opposite the pole pieces of magnets R will produce corresponding sound currents in said magnets R, which will flow in the described circuiting and be reproduced at speaker 284.

To make a recording, switch 254 is thrown to "record" position, erasing circuit switch 234 is closed, motor reversing switch S is placed in proper position to cause the tape to be driven in whichever direction is desired, switch 237 is either placed in open or closed position, depend-

ing upon which lane of the tape is to be recorded on first, and line switch 290 is then closed. Tape T will then be driven ahead, its past history will be obliterated by the erasing or polarizing magnets located ahead of the recording magnets, and an amplified voice current, flowing in recording magnets R due to a voice input to microphone M, will be recorded on the lane of the tape which is then in alignment with the recording magnet pole pieces. When the tape has thus been run through the machine, switch S is reversed to cause the tape to be driven in the reverse direction, and switch 237 is operated to shift the recording head so as to move its pole pieces over into alignment with the other half of the tape. A recording is then made on the other half or lane of the tape. Thus two adjacent recordings are made on the tape, which, as here described, extend in directions contrary to one another. It will of course be evident that if desired, the two recordings may extend in the same direction along the tape simply by running the tape back to its beginning point at the end of the recording on the first lane, and then starting the second recording on the same end of the tape as before.

Fig. 8 is similar to Fig. 3 but shows a modification, in which the recording head is stationary and the tape guide arms move transversely of the tape, so as to effect the necessary relative movement between recording head and tape by moving the tape in a transverse direction rather than moving the recording head. The recording head, designated at 60a, is again made of blocks 110 and 111, which may be identical to the recording head blocks of the previously described form of the invention, and which may be understood to have polarizing and translating magnets and a way for the tape all identical to the corresponding members in the previously described form. Block 110 is mounted on the outer end of a plug member 310, adapted to be removably mounted in a socket member 311 mounted on the outer end of a hollow post 312 mounted on panel 15, the hollow within post 312 receiving the cable 313 comprising the conductors connected to the magnets within the recording head. Tape guide members 315, exactly like those described in connection with Figs. 3 and 4, are mounted on the ends of arms 316 and 317, the latter supporting said guide members opposite the two ends of the recording head, as indicated, and being themselves carried by a shaft member 320 having a longitudinally slidabile fit within a bore 321 formed in mounting member 322 secured to panel 15. The rearward end of shaft member 320 is formed with screw threads 324 of coarse pitch, and engaging the screwthreaded portion of the shaft, between mounting member surface 325 and a cover plate 326 secured to mounting member 322, is a nut member 327 similar to nut 167 in the form of Fig. 3, said nut member being operated by an extending arm 328 exactly as described in connection with the previous form of the invention.

Aside from the modifications now described, the form of Figs. 8 and 9 may be exactly similar to the previously described form of the invention, movement of nut 327 by means of arm 328, accomplished for example as described in connection with the previous form of the invention, effecting longitudinal movement of shaft 320 and tape guide members 315 to shift the tape in a lateral direction with reference to the sound head and magnets carried thereby. The tape may thus be shifted in such a manner that the record-

ings made thereon will extend along adjacent, non-overlapping lanes of the tape, so that a multiplicity of adjacent recordings may again be made on a single magnetic tape.

Certain specific illustrative forms of the invention have now been described, although it will be understood that the description here given is for illustrative purposes only, and that various changes in design, structure and arrangement may be made without departing from the 10 spirit and scope of the invention or of the claims appended hereto.

I claim:

1. In a magnetic sound recording system, the combination of a flat magnetizable tape, a sound head comprising a pair of erasing magnets, a pair of translating magnets, and another pair of erasing magnets, arranged in tandem, the magnets of each of said pairs having pole pieces between which said tape may be driven and which are all adapted and positioned to coat selectively with a limited width lane of the tape, guide means adapted to guide said tape to travel between the pole pieces of said pairs of magnets, means for driving said tape in either direction, 15 electric circuiting for energizing the erasing magnets, switching means for connecting said circuiting to that pair of erasing magnets which is positioned ahead of the translating magnets for each direction of travel of the tape, and means for effecting relative transverse movement between said sound head and said tape guided by said guide means, whereby recordings may be made on different, non-overlapping longitudinally extending lanes of said tape.

2. In a magnetic sound recording system, the combination of a flat magnetizable tape, a sound head comprising a pair of erasing magnets, a pair of translating magnets, and another pair of erasing magnets, arranged in tandem, the 20 magnets of each of said pairs having pole pieces between which said tape may be driven, and which are all adapted and positioned to coat selectively with a limited width lane of the tape, guide means adapted to guide said tape to travel between the pole pieces of said pairs of magnets, means for driving said tape in either direction, 25 electric circuiting for energizing the erasing magnets, switching means for connecting said circuiting to that pair of erasing magnets which is positioned ahead of the translating magnets for each direction of travel of the tape, and means for shifting said sound head in a direction transversely of said tape, whereby recordings may be made on different, non-overlapping lanes of said tape.

3. In a magnetic sound recording system, the combination of a flat magnetizable tape, a sound head comprising a pair of erasing magnets, a pair of translating magnets, and another pair of erasing magnets, arranged in tandem, the magnets of each of said pairs having pole pieces between which said tape may be driven, and which are all adapted and positioned to coat selectively with a limited width lane of the tape, 30

guide means adapted to guide said tape to travel between the pole pieces of said pairs of magnets, means for driving said tape in either direction, electric circuiting for energizing the erasing magnets, switching means for connecting said circuiting to that pair of erasing magnets which is positioned ahead of the translating magnets for each direction of travel of the tape, and means for shifting said guide means and tape relatively to said sound head in a direction transversely of the tape, whereby recordings may be made on different, non-overlapping longitudinally extending lanes of said tape.

4. In a magnetic sound recording system, the combination of a flat magnetizable tape, a sound head comprising a pair of erasing magnets, a pair of translating magnets, and another pair of erasing magnets, arranged in tandem, the magnets of each of said pairs having pole pieces between which said tape may be driven and which are all adapted and positioned to coat selectively with a limited width lane of the tape, guide means adapted to guide said tape to travel between the pole pieces of said pairs of magnets, means for driving said tape in either direction, means for reversing the direction of longitudinal movement of the tape at a given point in its travel, and electric circuiting including switching means operable to energize selectively that pair of erasing magnets which is positioned ahead of the translating magnets for each direction of travel of the tape, said switching means being automatically operated by virtue of the reversal of the direction of travel of the tape at said given point in its travel, and means for effecting relative transverse movement between said sound head and said tape guided by said guide means, whereby recordings may be made on different, non-overlapping longitudinally extending lanes of said tape.

5. In a magnetic sound recording system, the combination of a flat magnetizable tape, a sound head comprising a plurality of pairs of erasing and translating magnets, arranged in tandem, between the respective magnets of which the tape may successively pass, said pairs of magnets including a pair of erasing magnets positioned ahead of a pair of translating magnets for each of the two directions of travel of the tape, the magnets of each of said pairs having pole pieces adapted and positioned to coat selectively with a limited width lane of the tape, guide means adapted to guide said tape in its path between the magnets of said pairs of erasing and translating magnets, means for driving said tape in either direction, electric circuiting for energizing the pair of erasing magnets positioned ahead of the pair of recording magnets for each direction of travel of the tape, and means for effecting relative transverse movement between said sound head and said tape guided by said guide means, whereby recordings may be made on different, non-overlapping longitudinally extending lanes of said tape.

HERMAN S. HELLER.
